H. J. ARMSTRONG

SPACER FOR DIPPER HANDLES

Filed Oct. 1, 1925

UNITED STATES PATENT OFFICE.

HARLEY J. ARMSTRONG, OF SEATTLE, WASHINGTON, ASSIGNOR TO THE MARION STEAM SHOVEL COMPANY, OF MARION, OHIO, A CORPORATION OF OHIO.

SPACER FOR DIPPER HANDLES.

Application filed October 1, 1925. Serial No. 59,901.

To all whom it may concern:

Be it known that I, HARLEY J. ARMSTRONG, a citizen of the United States, residing at Seattle, in the county of King and State of Washington, have invented certain new and useful Improvements in Spacers for Dipper Handles, of which the following is a specification, reference being had therein to the accompanying drawing.

10 This invention relates to spacers for dipper handles and the like and is designed more particularly for use with the dipper handles of power operated shovels.

In power operated shovels as usually constructed the boom is comprised of two members spaced apart to form an opening or guideway through which the dipper handle extends and in which it has both longitudinal and swinging movement. The dipper handle is formed of two parallel members or bars which are spaced apart throughout their entire length except for a short distance at the forward end of the handle where they are connected together by a spacer block rigidly mounted between them. As a result of this construction any lateral thrust imposed upon the handle will force one handle member against the adjacent boom member and the pressure will tend to bend or spring the handle member inwardly at its point of contact with the boom and to correspondingly displace the rearward end of the handle member outwardly. In the course of time repeated side thrusts of this kind will so distort the dipper handle as to render it practically inoperative.

One object of the present invention is to provide means for preventing the distortion of the dipper handle by the lateral thrusts to which it is subjected.

A further object of the invention is to provide the dipper handle with a spacer which will cause the strains to which the handle members are subjected to be transmitted to the boom; and which will not interfere with the normal operation of the dipper handle.

A further object of the invention is to provide a spacer of this character which will be very simple and inexpensive in its construction and which can be easily applied to the boom and dipper handle.

Other objects of the invention will appear as the device is described in detail.

In the accompanying drawings Fig. 1 is 55 a side elevation, partly broken away, of portions of the boom, dipper handle and dipper; Fig. 2 is a side elevation, partly broken away, of portions of the boom and dipper handle with the spacer in an inoperative position; Fig. 3 is a plan view of a portion of the dipper handle and spacer; and Fig. 4 is a transverse section taken on the line 4—4 of Fig. 1.

In these drawings I have illustrated one embodiment of my invention and have shown the same as applied to a boom and dipper handle of a well known construction but it will be understood that this embodiment has been chosen for the purpose of illustration only and that the invention may take various forms and may be applied to booms and dipper handles of various kinds.

As here shown the boom 1 comprises two parallel side members which are spaced apart to provide an opening or guideway between them, for a portion of their length. Extending through this opening in the boom is a dipper handle 2 which also consists of two side members or bars which are spaced apart for substantially their full length and on the forward end of which is mounted the excavating dipper 3. The forward portions of the two handle members are connected one to the other by a spacer block 4 which is rigidly secured in a position between them but which is of relatively short length. The two handle members are provided on their lower edges with toothed racks 5 which mesh with pinions 6 on a shipper shaft 7 mounted on the boom and rotated by a crowding motor or engine, not here shown, thus imparting longitudinal movement to the dipper handle. The racks are held in mesh with the pinions by means of a yoke carried by the boom and here shown as a standard 8 mounted on the shaft 6, extending upwardly between the two handle members and provided on its upper end with a transverse portion or head 9, the lateral portions of which overlap the upper edges of the handle members.

To prevent the distortion of the handle members by lateral strains to which they may be subjected I interpose between those portions of the handle members which lie between the boom members and spacer which is held against movement with the handle

so that it will lie between the handle members within the boom in practically all positions of the handle, and which is of such a character that the lateral thrust imposed upon one handle member will be transmitted through the spacer to the other handle member and to the boom member with which the last mentioned handle member is in contact, thus positively preventing the distortion of the handle members. As here shown, this spacer is in the form of an elongated block 10 which is provided at its rear end with pivot lugs 11 embracing a pivot lug 12 carried by the head 9 of the yoke and which are connected thereto by means of a pivot pin 13. This block is of such a width that it will fit snugly between the handle members and it may extend forwardly between the boom members any desired distance which will not interfere with the operation of the handle. In the present instance, it projects forwardly a little more than half the width of the boom. The forward end of the spacer block is provided with a part to engage the handle and limit the downward movement of the block and thus support the same between the handle members. In the device here shown, the forward end of the spacer is provided with laterally extending lugs 14 which rest upon the upper edges of the handle members. The forward edge of the spacer block is preferably curved, as shown at 15, after the manner of a sled runner, the purpose of which will hereinafter appear. The spacer block may be of any suitable material and construction and it is here shown as a steel casting cored out for the sake of lightness and having transverse ribs or partitions 16 to rigidly brace the side walls thereof one against the other and thus provide the necessary strength.

It will be apparent, therefore, that the spacer block will be supported between those portions of the handle members which lie within the boom in practically all positions of the dipper handle. However, when the dipper handle is retracted to the limit of its rearward movement the spacer block 4 at the forward end thereof will enter the space between the boom members and in doing so will engage the curved forward end of the spacer to move the same upwardly about its axis and out of the path of the spacer block 4, thus avoiding any interference with the movement of the dipper handle. When the handle is again moved forwardly the spacer 10 will move by gravity into its position between the handle members. Should the operator permit the handle to spring downwardly and rearwardly to a position beyond its vertical center the spacer will hang in a vertical position and the dipper handle will move away from the same but this is unimportant

as the dipper handle is not likely to be subjected to lateral strains when in this position and as soon as it is again moved forward to an operative position the spacer will assume its position between the handle members.

While I have shown and described one embodiment of my invention, I wish it to be understood that I do not desire to be limited to the details thereof as various modifications may occur to a person skilled in the art.

Having now fully described my invention, what I claim as new and desire to secure by Letters Patent, is:

1. In a mechanism of the character described, the combination with a boom comprising two members spaced apart, and a dipper handle extending between said boom members, capable of longitudinal movement and comprising two members spaced apart, of a spacer interposed between those portions of the handle members which lie between the two boom members and held against movement with said handle.

2. In a mechanism of the character described, the combination with a boom comprising two members spaced apart, and a dipper handle extending between said boom members, capable of longitudinal movement and comprising two members spaced apart, of a spacer carried by said boom and extending between those portions of said handle members which lie between said boom members.

3. In a mechanism of the character described, the combination with a boom comprising two members spaced apart, and a dipper handle extending between said boom members, capable of longitudinal movement and comprising two members spaced apart, of a spacer movably supported on said boom and normally extending between those portions of said handle members which lie between said boom members.

4. In a mechanism of the character described, the combination with a boom comprising two members spaced apart, and a dipper handle extending between said boom members, capable of longitudinal movement and comprising two members spaced apart, of a spacer pivotally supported on said boom, arranged to extend between those portions of said handle members which lie between said boom members and having a part to engage said handle and support said spacer between the handle members.

5. In a mechanism of the character described, the combination with a boom comprising two members spaced apart, and a dipper handle extending between said boom members, capable of longitudinal movement and comprising two members spaced apart, of a spacer pivotally supported on said boom, extending normally between those

portions of said handle members which lie between said boom members and having its forward end curved.

6. In a mechanism of the character described, the combination with a boom comprising two members spaced apart, and a dipper handle extending between said boom members, capable of longitudinal movement and comprising two members spaced apart, 10 and having a spacing block rigidly mounted between the forward portions thereof, of a spacer pivotally supported at its rear end on said boom, extending normally between those portions of the handle members which 15 lie between said boom members and having its forward end curved, whereby when said dipper handle is fully retracted the spacer block at the forward end of said handle will engage said pivoted spacer and move the 20 same out of its path.

7. In a mechanism of the character described, the combination with a boom comprising two members spaced apart, and a dipper handle extending between said boom members, capable of longitudinal movement and comprising two members spaced apart, 25 of a spacer pivotally supported at its rear end on said boom, arranged to extend between those portions of the handle members

which lie between the boom members and 30 provided at its forward end with laterally extending lugs to engage the upper edges of said handle members and support said spacer between said members.

8. In a mechanism of the character described, the combination with a boom comprising two members spaced apart, a dipper handle extending between said boom members and comprising two members spaced apart, 35 each of said handle members having 40 toothed racks along their lower edges, a shaft mounted on said boom, pinions carried by said shaft and meshing with said toothed racks to impart longitudinal movement to 45 said handle, and a yoke carried by said boom, extending between said handle members and having at its upper end portions 50 overlying the respective handle members to retain said racks in mesh with said pinions, of a spacer block pivotally mounted on said 55 yoke, extending forwardly therefrom between said handle members and having means for engaging said handle members to limit the downward movement thereof about its axis.

In testimony whereof, I affix my signature hereto.

HARLEY J. ARMSTRONG.
